UNITED STATES PATENT OFFICE.

EDWIN W. MAHONE, OF MARSHALL, TEXAS.

HARNESS-COLLAR.

1,211,207.

Specification of Letters Patent. Patented Jan. 2, 1917.

Application filed May 24, 1916. Serial No. 99,505.

To all whom it may concern:

Be it known that I, EDWIN W. MAHONE, a citizen of the United States, residing at Marshall, in the county of Harrison and State of Texas, have invented a new and useful Improvement in Harness-Collars, of which the following is a specification.

This invention relates to harness collars such as are frequently intended for horses, mules and the like.

10 Harness collars are usually made in different sizes, each size being about one inch larger than the next smaller size. The different size collars are relatively non-adjustable, and the dealers usually have to carry a complete stock on hand in order to be able to supply the demand for the different sizes. Moreover, such adjustment as may be possible in old styles of collars by drawing the fastening straps tighter or 20 looser, must be found anew each day.

The principal object of the present invention is to provide a collar having adjustable fastening means which preferably are also adjustable as between themselves whereby 25 a better adjustment of the collar is made possible.

With the foregoing and other objects in view which will appear as the description 30 proceeds, the invention resides in the combination and arrangement of parts herein-after specified, it being understood that changes in the precise embodiment of the invention herein disclosed can be made within 35 the scope of what is claimed without departing from the spirit of the invention.

In the accompanying drawings forming part of this specification, Figure 1 is a perspective view of the end portions of the harness collar equipped with the improvements 40 of the present invention. Fig. 2 is a plan view of the construction illustrated in Fig. 1. Fig. 3 is a longitudinal section through one of the end flaps showing the means for 45 adjustably securing the fastening devices in position.

Like reference numerals indicate corresponding parts in the different figures of the drawing.

50 The end portions of the harness collar are indicated respectively by the numerals 1 and 2. Stitched to or otherwise connected with the end portion (1) is a flap (3), which is made up preferably of an inside layer of 55 felt and an outside layer of leather or other backing material. A similar flap (4) is

suitably connected with the end portion (2) so as to overlap the flap (3). Suitably connected with the free end of the inner flap (3) is a metallic cross piece, having its free ends reversely bent to form the clips or guides (5) which slidably embrace or engage the flap (4), thus serving to hold the two flaps in adjustable engagement with each other.

65 The means for securing the collar in position preferably comprises a pair of buckles (6-6) adjustably connected with the flap (3) and a pair of straps (7-7) adjustably connected with the flap (4).

70 The means for adjustably connecting the straps (7-7) with the flap (4) preferably includes pairs of openings (8-8) which extend through the flap (4) as shown in Fig. 2, and are adapted each to receive a bolt 75 (9) which extends through an opening in the strap (7) and has applied to its outer end a wing nut (10). By removing the two wing nuts (10) the bolts (9) can be taken out of one set of openings (8) and adjusted 80 into any other one of the sets of openings (8) after which the wing nuts can be applied. The wing nuts can be tightened up sufficiently to compress the felt and thus draw the head of the bolt (9) in out of the way of 85 the animal's neck.

86 The buckles (6-6) are adjustably secured to the flap (3) by means of the wing nuts (11-11) in exactly the same way that the strap (7) is adjustably secured to the flap (4).

90 Thus, in effect, there is provided a combined adjusting and fastening means having connected elements, arranged in pairs, one pair embodying the elements 4 and 7 and the other pair the elements 3 and 6, or the equivalents thereof, one element, 3 or 4, being carried by and preferably per-

95 manently attached to the extremity of one member or side, 1 or 2, of the collar, and adapted to overlap the corresponding ele-

100 ment, 4 or 3, of the other pair, and the other element, 6 or 7, of each pair being adjustably mounted upon or connected to the related first named element, 3 or 4, of

105 the same pair, for movement or placement in a direction longitudinally of itself and the collar members, said second-named ele-

110 ments of the two pairs being mutually en-

gageable, as for example by reason of their tongue and buckle formation, and adapted for relative longitudinal adjustment. The elements represented by the tongue and

buckle, while bodily adjustable relatively to the elements 4 and 3, respectively, are adapted to be more or less permanently locked at the desired adjustment in fitting the collar, primarily, to the animal's neck, after which the temporary engaging means, represented by the tongue and buckle formation may be utilized in applying and removing the collar, any further and finer adjustment of the 10 collar members which may be necessary to secure a proper "fit" being effected through the relative adjustment of the tongue and buckle, which adjustment is in the same direction as the above noted bodily adjustment 15 of said elements.

The range of adaptability in size, by reason of the described adjustments, is such as to materially simplify the problems of manufacturers and dealers in providing collars 20 for different sized animals, and makes it possible for the user to change a collar at any time to suit an animal of a different size from that for which it is adjusted.

Having thus described the invention, what 25 is claimed as new is:

1. A combined harness - collar adjusting and fastening means, having connected elements arranged in pairs, one element of each pair being attached to and carried by 30 the extremity of one member of a collar and adapted to overlap the corresponding element of the other pair, and the other element of each pair being adjustably connected, for longitudinal movement, with the 35 first-named element of the same pair, the

second-named elements being mutually engaged for relative longitudinal adjustment.

2. A combined harness - collar adjusting and fastening means, having connected elements arranged in pairs, one element of 40 each pair being attached to and carried by the extremity of one member of a collar and adapted to overlap the corresponding element of the other pair, and the other element of each pair being adjustably connected, for longitudinal movement, with the 45 first-named element of the same pair, and means for permanently locking the second-named elements in their adjusted relations with the first-named elements, the second-named elements being provided with adjustably related temporary engaging devices. 50

3. A harness collar having its end portions provided with overlapping flaps, the inside flap being provided at its free ends 55 with guides adapted slidably to engage the outside flap, each of the said flaps having a series of openings therein, a buckle for one of said flaps, a tongue for the other of said flaps, a bolt and wing nut for adjustably 60 holding said buckle in any one of the openings of said flaps, and a bolt and wing nut for adjustably holding said tongue in engagement with any one of the openings of said flap.

EDWIN W. MAHONE.
